UNITED STATES PATENT OFFICE.

ALBERT PATITZ, OF MERIDEN, CONNECTICUT, ASSIGNOR TO THE BRADLEY & HUBBARD MANUFACTURING COMPANY, OF SAME PLACE.

DESIGN FOR A BASE FOR LAMP-FOUNTS.

SPECIFICATION forming part of Design No. 24,134, dated March 19, 1895.

Application filed February 18, 1895. Serial No. 538,902. Term of patent 3½ years.

To all whom it may concern:

Be it known that I, ALBERT PATITZ, of Meriden, in the county of New Haven and State of Connecticut, have invented a new Design for a Base for Lamp-Founts, (Case C;) and I do hereby declare the following, when taken in connection with the accompanying drawings and the letters of reference marked thereon, to be a full, clear, and exact description of the same, and which said drawings constitute part of this specification, and represent, in—

Figure 1, a side view of a base for lamp-founts embodying my design; Fig. 2, a bottom plan view of the same.

This invention relates to a design for a base for a lamp-fount, and the design consists in the configuration and ornamentation as shown in the accompanying illustrations.

In general outline the base is square, contracting gradually toward the upper edge or neck, and terminating at its lower edge in four legs A, formed by upwardly springing, spreading acanthus leaves B, meeting at the center

side, as at C, and having upwardly curved scroll feet D. At the upper edge the base curves inward and contracts slightly, and from the upper edge or neck E, conventionalized acanthus leaves F droop over each corner, meeting the upwardly branching leaves B, the foliations of the leaves F overlying a lattice-work G, which fills the spaces between the corners and incloses a floriated open medallion H, all as shown in the accompanying illustrations.

I claim—

The design for a lamp-fount base, as described and shown in the accompanying illustrations.

In testimony whereof I have signed this specification in the presence of two subscribing witnesses.

ALBERT PATITZ.
